AIR CHAMBER FOR WELL PUMPING

Application filed June 20, 1930. Serial No. 462,668.

Our present invention has reference to pumps for deep wells in which the tubing of a pump will have sucker rods for lifting the fluid, and our object is to connect to the tubing above the working barrel and cups of the well a tubular air chamber which is of a materially greater cross sectional diameter than that of the tubes, and which has its ends or heads provided with openings that align 10 with the bores of the tubes and have arranged in these openings tubes that extend toward each other and which have their confronting ends spaced a suitable distance away from each other, whereby the fluid column, during 15 the pumping operation will come in contact with the air column in the air chamber and form a cushion to relieve shock when the reciprocating sucker rod makes its lifting stroke, while the space between the lower tube 20 and the bottom of the air chamber provides a fluid pocket.

To the attainment of the foregoing the invention consists in the improvement herein-after described and definitely claimed.

25 In the drawing:

Figure 1 is a substantially central transverse sectional view through our improvement connected to the tubes of a deep well pump.

30 Figure 2 is a transverse sectional view approximately on the line 2—2 of Figure 1.

Figure 3 is a detail elevation with parts in section to illustrate a cup element arranged on the upper head of the improvement for 35 providing a catch basin therefor.

The tubing pipes for the well are indicated by the numerals 1 and 2, respectively. The tubes 1 and 2 have their ends threaded and are screwed in the reduced neck portions of 40 heads 3 and 3', respectively. The bodies of both of the heads are of a materially greater cross sectional diameter than that of the tubes 1 and 2, the said bodies being round in plan, and the head 3' preferably has its body 45 rounded inwardly toward the left portion thereof. The body of the head 3, however, is of a substantially equal thickness throughout and has its face, between its peripheral corner and its neck concaved, as indicated by the 50 numeral 3'' in the drawing. The purpose for

the formation of the head 3, especially the concaved wall or outer face thereof, is to prevent metal or rock dropping down the well, as the air chamber is arranged in close proximity to the wall of the well. The neck 55 portions of both of the heads 3 and 3' are of a suitable size and dimension to permit the same being engaged by standard size slip sockets should the tubing break at its point of connection with the said heads, this being 60 especially true with respect to the neck of the head 3 and as disclosed by the drawing the neck of this head is exteriorly as well as internally threaded.

The confronting ends of the heads 3 and 3' are reduced and exteriorly threaded and there is screwed upon these threads and welded to the ends of a cylindrical member 4 that provides the air chamber. Any desired number of air chambers may be employed but 70 all of the same are located a suitable distance above the working barrel and the cups carried by the sucker rods of the well. The heads 3 and 3' are each provided with bores 5 in alignment and screwed in the respective 75 bores there is an upper tube 6 and a lower tube 8. The upper tube 6 may comprise a plurality of sections suitably coupled and the lower tube 8 is of a less length than the upper tube 6. The confronting ends of the tubes 80 6 and 8 are spaced from each other and the said ends are flared outwardly or provided with bell-shaped mouths 9 and 10, respectively. The longer upper tube 6 is held centrally in the chamber 4 through the medium 85 of several open spacer members 11, that are fixed in the chamber 4, or on the pipe 6.

The sucker rod is indicated by the numeral 14. The sucker rod has fixed thereon the 90 usual cups that are arranged at a distance below the air chamber. The rod 14 is reciprocated in the usual manner and by virtue of such reciprocation will lift the fluid from the bottom of the well and direct the 95 same through the tubes 2, 8, 6 and 1. By providing the tubes 6 and 8 with the flared or bell-shaped mouths 9 and 10 the cups will pass freely from one tube into another when inserted in or removed from the well. There 100

is necessarily a column of air in the upper portion of the air chamber 4, and this air column is contacted by the fluid column lifted by the cups on the rod 14, and such air

tubes having their confronting ends bell-shaped and spaced away from each other.

In testimony whereof we affix our signatures.

HAROLD G. DURNELL.
SAMUEL T. STEEL.

8 column forms the cushion necessary to relieve the shock when the rod 14 acts on its vertical stroke to lift the fluid. The space between the mouth of the lower tube 8 and the lower head 3, of course, receives a quantity of fluid 10 therein but the overflow of fluid will be returned into the tubes and this space affords a pocket for sand lifted from the well by the pumps. Obviously the well may be provided with any desired number of air chambers similar 15 to that herein set forth, each of which, however, is arranged above in the pipes or well proper, at suitable intervals, according to the depth of the well.

20 The construction and advantages will, it is thought, be apparent to those skilled in the art to which such invention relates so that further detailed description will not be required.

25 If desired and as illustrated by Figure 3 of the drawing we may arrange upon the top of the head 3 of the air chamber a cup-shaped member 15'. This member serves as a basin to receive therein metal, rock or other materials that drop into the well to prevent such 30 materials interfering with the operation of the pump or damaging the same.

35 From experience we have found that unless the upper tube 6 is rigidly supported by a plurality of the open spacer members 11, the same incident to the vibration to which the said tube is subjected is liable to break at its point of connection with the head 3, and, therefore, it is an absolute requirement that 40 number of such spacer members be employed.

45 Obviously if desired, the tubes 6 and 8 may be in the nature of a single element and may be provided with a series of concentrically arranged openings therethrough which communicate with the air chamber or chambers.

45 Having described the invention, we claim:

50 An air chamber designed to be connected with the tubing of a pumping well having sucker rods for lifting the fluid, comprising heads having socket ends connected to two of the spaced and alining tube sections, said heads, from their said sockets being gradually widened outwardly, and having their ends provided with peripheral threads, a tubular member screwed on said threads and comprising 55 an air chamber, said heads having bores alining with the bores of the well tubing, and the bores from the inner ends of the heads being enlarged and threaded, tubes having 60 their ends screwed in the last mentioned portions of the heads, the upper tube being of a greater length than the lower tube, means holding the upper tube in spaced relation with respect to the air chamber and in parallelism with the lower tube, and both of said 65
